Primary Examiner — Cathron Brooks(74) *Attorney, Agent, or Firm* — Wilmer Cutler Pickering Hale and Dorr LLP(57) **CLAIM**

The ornamental design for a display screen with graphical user interface, as shown and described.

DESCRIPTION

FIG. 1 is a front view of a display screen with graphical user interface showing my new design; and, FIG. 2 is a front view of a second embodiment thereof. The broken lines shown, including dotted lines, dashed lines, heavy broken lines and light broken lines, all illustrate portions of the display screen with graphical user interface that form no part of the claimed design.
